O. H. HALVERSON

CHECK BOOK BLOTTER

Filed Feb. 23, 1923

INVENTOR
O. H. HALVERSON
BY Munn Co.

ATTORNEYS

UNITED STATES PATENT OFFICE.

ORRIS H. HALVERSON, OF MANITOWOC, WISCONSIN.

CHECK-BOOK BLOTTER.

Application filed February 23, 1923. Serial No. 620,783.

To all whom it may concern:

Be it known that I, ORRIS H. HALVERSON, a citizen of the United States, and a resident of Manitowoc, in the county of Manitowoc and State of Wisconsin, have invented a new and useful Improvement in Check-Book Blotters, of which the following is a full, clear, and exact description.

My invention relates to improvements in check book blotters, and it consists in the combinations, constructions, and arrangements herein described and claimed.

An object of my invention is to provide a check book blotter which is adapted to be readily secured to the holder of a check book.

A further object of my invention is to provide a device of the type described which is adapted to overlie the uppermost check and stub of the check book, whereby it may be readily used when desired.

A further object of my invention is to provide a device of the type described in which the blotter may be also used as an advertising medium.

A further object of my invention is to provide a device of the type described which is simple in construction and which is durable and efficient for the purpose intended.

Other objects and advantages will appear in the following specification, and the novel features of the invention will be particularly pointed out in the appended claim.

My invention is illustrated in the accompanying drawings forming part of this application, in which—

Figure 1 is a plan view of the blotter attachment,

Figure 2 is a perspective view of a check book and holder showing the blotter operatively applied thereto,

Figure 3 is an enlarged sectional view of a portion of the device, and

Figure 4 is a perspective view of a check book showing the modified form of my device operatively applied thereto.

In carrying out my invention I make use of a check book indicated generally at 1, and a check book holder 2. The book 1 is ordinary in construction and is provided with a flap 3 by means of which the book is removably secured to the holder 2. The portion 4 of the holder 2 consists of two pieces which are sewn together by stitching 5. It will therefore be observed that the

holder 4 provides a pocket into which the flap 3 is adapted to extend. The parts thus far described are ordinary in construction, and form no part of my invention except 60 is so far as they cooperate with the parts about to be described.

I then provide a blotter attachment which is clearly shown in Figure 1. This attachment comprises a flap 6, a piece of cardboard 7, and a blotter 8. The blotter 8 and cardboard 7 are the same size as the check book 1. The blotter 8 is secured to the board 7 65 by any means, such as a strip of tape 9.

From the foregoing description of the various parts of the device, the operation thereof may be readily understood. The blotter attachment is adapted to be removably secured to a holder by means of the flap 6. The board 7 is disposed beneath the check book 1 so as to align the flap 6 with 70 the flap 3. Both of the flaps are now inserted in the pocket 10 which is formed by the two pieces of the portion 4. As heretofore stated, the board 7 is of the same size as the check book 1. This construction 75 disposes the tape 9 at the free end of the check book 1. The tape 9 in turn permits the blotter 8 to rest upon the uppermost check and stub of the check book.

When using the device, the blotter 8 is 80 swung out of the way with respect to the check and stub so that the person may write upon the check. After the check has been “made out” the blotter 8 is swung on to the check so as to blot the latter. In this manner 85 the check may be instantly removed from the book when it is “made out” without the danger of the check being smeared.

The blotter 8 serves a double function in that it not only acts as a blotter, but also 90 provides an advertising medium for the bank. In Figure 2 I have shown the outer side of the blotter as being provided with a fictitious name. It is obvious that the banks can place their names upon the blotters or can place any other information 95 upon the blotter which they may wish. The board 7 and the blotter 8 are adapted to be bent at their mid-portions when the holder 2 is closed. It is obvious that the blotter 100 can be used for all of the checks in the bank book since it is merely swung into open position when a check is being written upon or removed from the check book. When the entire book of checks has been used, the 105 110

blotter may be used with the new check book. In this manner, the same blotter may be used for a great length of time.

In Figure 4 I have shown a modified form 5 of the device. In this form the blotter 20 is secured to the lowermost check 21 of the check book 22 by means of a strip of tape 23. In this form of the device the blotter 20 is used in much the same manner as is 10 the blotter 8. It will be noted, however, that the blotter can only be used during the life of the check book to which it is attached, and the blotter is thrown away when 15 the book is used. In other words, this form of the device can only be used with one check

I claim:

In a check book blotter construction for check books, of the type having a cover with 2 a flap receiving recess therein, a check book having a flap adapted to be received in said recess, said blotter construction comprising a flap adapted to be received in said recess, a check book supporting member hingedly 25 secured to said letter flap, and a blotter hingedly secured to the free end of said member and adapted to overlie the uppermost check in the check book.

ORRIS H. HALVERSON.
